UNITED STATES PATENT OFFICE.

JOHN H. EWING AND EDWARD L. BILL, OF WHEELING, WEST VIRGINIA.

LAMP AND LANTERN.

SPECIFICATION forming part of Letters Patent No. 275,474, dated April 10, 1883.

Application filed August 24, 1882. (No model.)

To all whom it may concern:

Be it known that we, JOHN H. EWING and EDWARD L. BILL, of Wheeling, in the county of Ohio and State of West Virginia, have invented certain new and useful Improvements in Lamps and Lanterns; and we do hereby declare the following to be a full, clear, and exact description of the invention, such as will enable others skilled in the art to which it pertains to make and use the same.

Our invention relates to an improvement in lamps and lanterns, and more particularly to globes and chimneys therefor, the object being to provide improved means for attaching lenses to the articles mentioned.

With this object in view our invention consists in certain details of construction and combination of parts, as will be hereinafter explained, and pointed out in the claims.

20 In the accompanying drawings, Figure 1 is a view in front elevation of a lantern-globe constructed in accordance with our invention. Fig. 2 is a view thereof in vertical section, and Figs. 3, 4, 5, 6, 7, and 8 show sectional views of modified forms which our invention may assume.

25 A represents a globe, which may be appropriately modified in size and shape to fit different styles of lanterns and lamps. It is constructed in any suitable and approved manner and provided during the process of construction with one or more flat-faced annular extensions, B, virtually consisting in projected portions of the globe. The outer ends of the said extensions are encircled by flanges C, which

30 are divided into two or more segmental sections by openings D, the same being designed to receive fingers E, which extend inwardly from the annular settings F of the lenses G, and which are arranged to coincide in position 40 with the position of the said openings D. In securing the lenses to the globes, the fingers are first introduced into the openings. When this is effected the lenses are revolved sufficiently to engage the fingers with the rear faces of the flange-sections. In detaching the lenses from the globes the said fingers are brought into positions of coincidence with the openings, thus disengaging them from the flange-sections and permitting the removal of

45 50 the lenses.

Crystal glass is preferably employed in the fabrication of the globes, which may be, if de-

sired, ground or flashed with colored glass, leaving the faces H of the extensions B untouched. As to the lenses themselves, they 55 may be formed from crystal or colored glass, and if crystal glass is employed in their fabrication, and it is desired to color the transmitted light, their inner or outer faces may be flashed, as shown at I in Fig. 3 of the drawings, with colored glass. The coloration of the transmitted light may also be effected by flashing the faces H with colored glass, as shown at J, or by the interposition of panes K, of colored glass, between the said faces H and 65 the lenses.

It is apparent that a lamp or lantern provided with a globe constructed in accordance with any of the above-recited methods will constitute a signaling apparatus easy to operate, 70 and having a very wide range of effect.

The extensions B are closed by their flat faces, and this is the preferred construction, inasmuch as the lenses may be manipulated without in any way disturbing the body of air 75 enclosed by the globe; but, if found desirable, the extensions may be left open.

In the modification shown in Fig. 3 of the drawings the lens is provided with resilient arms L, adapted to be sprung over the flange 80 M of the extension, which in this instance is not broken by openings.

Fig. 4 of the drawings shows a lens having arms N made integral with it, this type of lens being designed to be used in conjunction with 85 a flange, C, like the flange shown in Fig. 1 of the drawings.

The lens shown in Fig. 5 of the drawings is mounted in an annular metallic setting having a screw-threaded flange, O, projecting inwardly 90 from it, said flange being adapted to be screwed over a flangeless screw-thread extension, P.

In the modification shown in Fig. 6 of the drawings the setting of the lens is provided with a plain inwardly-projecting annulus, Q, 95 designed to be secured to the flangeless extension R by cement.

In Fig. 7 of the drawings a lens having an inwardly-extending flange, S, formed integral with it is shown, said lens being cemented to 100 flangeless extension T, provided with corrugations to offer a firm hold for the cement.

The lens shown in Fig. 8 of the drawings has an interiorly screw-threaded flange, U, formed

integral with it. This lens is illustrated as in engagement with a flangeless extension, V, provided with small projections W, which engage with the screw-threads of the flange U, and 5 take the place of continuous screw-threads shown in the flangeless extension P.

Our invention is not limited to globes and chimneys; but cylinders and all other glass articles for inclosing and protecting flames may 10 be adapted to have lenses attached to them in the manner shown.

In view, then, of the modifications above suggested, and others of like character which the invention embraces, we would have it understood that we do not limit ourselves to the exact construction shown and described, but that we hold ourselves at liberty to make such changes and alterations as fairly fall within the spirit and scope of our invention.

20 Having fully described our invention, what we claim as new, and desire to secure by Letters Patent, is—

1. The combination, with a globe or chimney having one or more flat-faced extensions, of lenses and devices associated with the lenses and arranged to engage with the peripheries 25 of the said extensions.

2. The combination, with a globe or chimney

having one or more flat-faced extensions encircled by flanges, of lenses and fingers attached 30 to or made integral with the lenses and arranged to be engaged with the flanges of the extensions, substantially as set forth.

3. The combination, with a globe or chimney having one or more flat-faced extensions encircled by flanges having openings in them, of lenses and fingers associated with the lenses and arranged to coincide with the openings in the flanges, substantially as set forth.

4. The combination, with a globe or chimney 40 having one or more flat-faced extensions, the same being encircled by flanges, of lenses, annular metallic settings in which the lenses are mounted, and fingers attached to or made integral with said settings, and arranged to engage with the flanges of the extensions, substantially as set forth.

In testimony whereof we have signed this specification in the presence of two subscribing witnesses.

JOHN H. EWING.
EDWARD L. BILL.
